Primary Examiner — John R Yeh*(74) Attorney, Agent, or Firm* — David T. Bennett(57) **CLAIM**

I claim the ornamental design for an adjustable bar clamp, as shown and described.

DESCRIPTION

FIG. 1 is a left perspective view of my new design for an adjustable bar clamp;

FIG. 2 is a right perspective view thereof;

FIG. 3 is a left exploded view thereof;

FIG. 4 is a left side view thereof;

FIG. 5 is a top view thereof;

FIG. 6 is a bottom view thereof;

FIG. 7 is a right perspective view of the clamp insert;

FIG. 8 is a left perspective view thereof; and,

FIG. 9 is a rear perspective view of the adjustable bar clamp in a state of use.

The broken lines in FIGS. 1-8 depict portions of the adjustable bar clamp that form no part of the claimed design. Additional broken lines in FIGS. 3 and 9 depict environment of the adjustable bar clamp and form no part of the claimed design.
